BOILER WATER LEVEL TESTING MEANS

Philip A. Jerguson, West Medford, Mass.

Application November 30, 1938, Serial No. 243,157

1 Claim. (Cl. 73—297)

This invention relates to boilers or like pressure containers and the object is to provide an improved construction whereby the installation and repair of the cocks by means of which the water level is observed is facilitated.

5 My invention will be well understood by reference to the following description taken in connection with the accompanying drawing wherein:

Fig. 1 is an elevation of a boiler showing gage 10 cocks and operating means therefor; and

Fig. 2 is a longitudinal section through one of the cocks.

As is well known, in steam power plants each boiler or steam drum is fitted with several gage 15 cocks each attached independently and directly. They are spaced equally in a vertical direction, and by opening each cock in succession an experienced man can tell by noting the appearance and sound of the blast from each cock approximately where the water level is. Thus the indication of the glass gages may be checked or the water level determined if there is no gage or the gage is out of service. In the ordinary installation, since these cocks are located adjacent the 20 normal water level of the boiler, they are far above the level of the fire-room floor and thus must be fitted with suitable mechanism for permitting their operation from the distance.

Thus, referring to Fig. 1, I have there shown in a general way a boiler having a steam drum 4 fitted with three gage cocks 6 equally spaced in a vertical direction and discharging to a spatter pan 5 which drains to pipe 7 leading to the bilge or other suitable place. To the stems of these cocks, which are of the screw-down type as more fully hereinafter to be described, are secured operating levers 8 from which depend rods 10 extending to a suitable station adjacent the fire-room floor where they are provided with handles 12. Obviously not only for appearance but for convenience the several levers 8 should be parallel, as should the depending rods, and to permit an accurate comparison of the indications of the escaping steam and water the extent of opening of the several valves should be uniform, both among themselves and in successive observations. Thus, for example, the arms being in the position indicated in Fig. 1, the desired open position might correspond to a 45° movement.

Under service conditions, due to corrosion and other causes, valves require repair, either by re-grinding the seats or refacing the valve head proper, or by both operations. Obviously in the case of a screw-down valve the removal of material from the seat or the valve changes, in the closed position of the parts, the angular position of the valve stem and consequently the position of an operating lever such as 8 attached thereto with a resulting disarrangement of the relation 50 of the parts at the operating station on the fire-

room floor. Hence when one or more valves have thus been repaired, it has been necessary to relocate the lever and in practice this operation has been inconvenient and time-consuming in itself and subject to errors in its execution.

5 In accordance with my invention I equip the boiler with valves such as are illustrated in detail in Fig. 2 comprising each a valve body 14 having the discharge opening 16 and provided with a seat 18 with which cooperates the valve proper or head 20 carried by the threaded stem 22. The thread on this stem works in an internally threaded block 24 having a flange 26 overlying the outer end of the valve body 14 and adapted to be clamped thereto by means of a flanged nut 28 15 screwing onto the exterior of the body. The outer end of the stem 22 is provided with a hexagonal or other non-circularly formed portion 30 to which is fitted the lever 8 secured by the nut 32.

When the cock is first installed on the boiler, 20 the stem is screwed down tight and the nut 28 is then slackened off slightly and the lever 8 adjusted to the correct angle, the block 24 rotating with it in this movement without longitudinal movement of the valve stem relative to the body 25 of the valve. The parts are held in this correct position by setting up the nut 28. Whenever repairs to the valve are made and a consequent change in the angular setting of the lever 8, a 30 quick and correct adjustment is made in the same manner, the operation requiring only a few minutes as compared with a tedious reconstruction by means of tools, often requiring hours, in the case of installations as hitherto known. It is thus easy to place the gaging mechanism in the 35 most convenient operating condition and to maintain it in such condition.

I am aware that the invention may be embodied in other specific forms without departing from the spirit or essential attributes thereof, and I therefore desire the present embodiment to be considered in all respects as illustrative and not restrictive; reference being had to the appended claim rather than to the foregoing description to indicate the scope of the invention.

45 I claim:

A steam generator having a series of vertically spaced cocks in the wall thereof, each comprising a casing having a valve seat and a horizontal threaded valve stem, an operating lever arm mounted on the stem in fixed angular relation 50 thereto and actuating mechanism pivoted to the extremity of the lever arm and depending therefrom to provide for operating the arm from a remote location to open and close the valve, a block having a female thread in which said stem 55 works, and means for clamping the block to the casing of the cock permitting free angular orientation thereof.

PHILIP A. JERGUSON.
